UNITED STATES PATENT OFFICE.

HAROLD D. THOMAS, OF CHICAGO, ILLINOIS, ASSIGNOR TO VESTA BATTERY CORPORATION, OF CHICAGO, ILLINOIS, A CORPORATION OF ILLINOIS.

SEARCHLIGHT FOR AUTOMOBILES.

Application filed June 9, 1920. Serial No. 387,725.

To all whom it may concern:

Be it known that I, HAROLD D. THOMAS, a citizen of the United States, residing at Chicago (5007 Vincennes Av.), in the county of Cook and State of Illinois, have invented certain new and useful Improvements in Searchlights for Automobiles, of which the following is a specification.

The present invention relates to search lights for automobiles and more particularly to mechanism for controlling the position of search lights on automobiles with reference to the road ahead.

It is the object of the invention to provide simple mechanism for limiting the motion of the search light to prevent interference with persons approaching it while admitting of manipulation of the light in other directions.

It is another object of the invention to provide mechanism for the purpose specified, by which a search light may be adapted for attachment to a vertical as well as to sloping supports, such as windshields.

It is the more specific purpose of the invention to provide simple mechanism which may be easily attached to prevailing types of search lights.

For a fuller understanding of the invention reference is had to the accompanying drawings in which—

Fig. 1 is an elevational view of a search light attached to a windshield and embodying the invention;

Fig. 2 is a plan view of the device shown in Fig. 1, partly in section on line 2—2; and Fig. 3 is a section on line 3—3, Fig. 1.

In the drawings 1 indicates a part of a wind shield. 2 the search light and 3 the clamp by which the search light is attached to the wind shield. The clamping arm 3' terminates in a support 4 for the vertical spindle 5 and the spindle 5 carries at its upper end a bearing 6 for the horizontal spindle 7, which in turn carries the search light. The parts referred to represent the prevailing type of search light support and do not form part of the invention.

The subject matter of the invention in the particular embodiment shown comprises two disks 8 and 9 of special construction and means for securing them as a unit upon the projecting end of spindle 7.

Both disks are provided with a relatively large number of uniformly spaced per-

forations 8' and 9', respectively, extending along circles of the same radius. The number of perforations on one disk is different from that of the other disk to obtain in substance the effect of the well-known vernier arrangement. By slight consecutive angular displacements of one disk relatively to the other two perforations will always register with one another so that by means of a screw the two disks may be held in any desired angular relation.

The inner disk 8 has a non-circular central aperture 10 to fit a complementary cross-sectional configuration of the spindle 7. As indicated the end 7' of the spindle 7 is flattened and the aperture 10 is shaped to fit it. This shows merely one of the many means by which the disk 8 may be secured to the spindle to turn with it.

The aperture 11 of disk 9 is large enough to slip over the spindle end. In order to securely attach the disk 9 to the disk 8, two screws 12 are used. The perforations 8' are threaded to receive the screws.

The outer disk 9 is non-circular. In the particular instance shown, the peripheral edge of the disk is defined by a circle and a chord or straight edge 13 which co-operates with the clamping arm 3' to normally limit angular movement of the spindle 7. A nut 14 may be used to secure the disks upon the end of spindle 7.

The operation is as follows:

In the position indicated in Figs. 1 and 2, the light 2 occupies its normal operative position with reference to the road ahead. The disks 8 and 9 are adjusted so that, whatever the angular relation of the wind shield or other support may be relatively to the vertical, the angular motion of the search light is limited in upward direction to the range determined by the co-operation between the straight edge 13 of disk 9 and arm 3'. This range is indicated by the two positions of disk 8 in Fig. 3. The light may assume all possible positions for illuminating the road between a few feet ahead of the vehicle to any desired distance ahead, but it cannot be raised above the horizontal or generally above any angle prescribed as the limit by laws or regulations. Once the device is set in accordance with these regulations, it is not possible for the driver to intentionally or accidentally change its position beyond the vertical limit.

If it is desired, however, to direct the light sideways to read signs or for other purposes of orientation, the light may be turned about the vertical spindle 6 and when the disk 8 has passed the arm 3', the light may be turned about spindle 7 to any desired extent. The utility of a search light is thus not interfered with while its dangerous attributes are eliminated.

10 It is understood that the element represented in the preceding description by the disk 9 may have any desired configuration. The essential characteristic is the provision thereon of stop elements co-operating in any predetermined way with the arm 3' or other equivalent structural element to limit the angular motion of the search light as described while retaining universal freedom of motion in all other directions.

15 20 While the subject matter of my invention involves a specific structural arrangement, there is considerable latitude in the execution of the various details.

The usual connection for affording universal movement of the light includes two spindles at right angles to each other, as shown in the drawings, one for angular movement in vertical planes and the other for movement in horizontal planes. It is to be noted that in the particular embodiment shown the normally vertical spindle may be inclined with respect to the vertical, as for instance when the windshield or other support is inclined or due to other causes.

30 35 For the sake of convenience I refer to this spindle, in the claims, as vertical spindle or as affording horizontal movement and do not intend to be limited to the strict interpretation of these terms.

40 I claim:

1. The combination with a searchlight, of an arm for attachment to a vehicle, a horizontal spindle on said searchlight and having a projecting end located substantially in the vertical plane through said arm when the searchlight is directed forwardly, a vertical spindle pivoted on said arm and providing a support for an intermediate portion of said horizontal spindle, a motion-limiting member and means for attaching it to the projecting end of the horizontal spindle, said member cooperating with said arm to limit the angular movement of the horizontal spindle when said projecting end lies in or within a predetermined range of movement from the vertical plane through the arm.

60 65 2. The combination with a searchlight, of an arm for attachment to a vehicle, a horizontal spindle on said searchlight and having a projecting end located substantially in the vertical plane through said arm when the search light is directed forwardly, a vertical spindle pivoted on said arm and providing a support for an intermediate por-

tion of said horizontal spindle, a member adapted to be connected to the projecting end of said horizontal spindle, a second member adapted to cooperate with said arm to limit the angular movement of the horizontal spindle and means for adjusting the two members relatively to each other.

3. The combination with a searchlight, an arm for attachment to a vehicle, a universal motion connection mounted on said arm and including an element turning about a horizontal axis and a member turning about a vertical axis, of a disk-shaped body attached to said element, a second disk-shaped body having a portion cooperating with said arm to limit the angular movement of the element about its axis, and means for connecting said bodies.

4. The combination with a searchlight, an arm for attachment to a vehicle, a universal motion connection mounted on said arm and including an element turning about a horizontal axis and a member turning about a vertical axis, of a disk-shaped body attached to said element, a second disk-shaped body having a portion cooperating with said arm to limit the angular movement of the element about its axis, and means connecting said bodies and permitting the angular adjustment of said second disk-shaped body with respect to said first disk-shaped body.

5. The combination with a search light, a support for attachment to a vehicle and a connection between the light and its support including a normally vertical spindle carried by the support and a normally horizontal spindle carried by the vertical spindle, of a disk-shaped body attached to said horizontal spindle and having a non-circular central opening and a circular series of perforations, a second disk-shaped body having a central opening of greater diameter than the central opening of the first body and a circular series of perforations differing in number from the first series, screw mechanism adapted to pass into the said perforations to interlock the said bodies, the second of said bodies having a non-circular peripheral edge forming a stop member in co-operation with the support.

6. An attachment for use with searchlight brackets of the type which includes an arm for attachment to a vehicle and a horizontal spindle which lies approximately in the vertical plane of the arm when the light is directed forwardly, said attachment comprising a member adapted to be fixed to the horizontal spindle, a second member, means for adjusting the two members relatively to each other, the second member having a portion which cooperates directly with the arm to limit the angular movement of the horizontal spindle.

7. A motion-limiting device for attachment to a rotatable element which is mov-

- ably supported upon an arm in such manner that a portion of said element may be moved into and out of vertical alignment with the supporting arm, said device comprising a disk-shaped body having a peripheral edge defined by a circle and a chord, the radius of the circle being greater than the vertical distance between the axis of said element and the supporting arm and the distance from the axis of the element to the edge formed by the chord being less than said vertical distance, and means for attaching said disk-shaped body to the portion of said element.
8. A motion-limiting device for attachment to a rotatable element which is movably supported upon an arm in such manner that a portion of said element may be

moved into and out of vertical alignment with the supporting arm, said device comprising a disk-shaped body having a peripheral edge defined by a circle and a chord, the radius of the circle being greater than the vertical distance between the axis of said element and the supporting arm and the distance from the axis of the element to the edge formed by the chord being less than said vertical distance, a second and smaller disk-shaped body having means permitting the fixing thereof upon the portion of said element, and means for connecting said disks.

In testimony whereof, I affix my signature.

HAROLD D. THOMAS.
